[57] CLAIM

The ornamental design for a head lamp, as shown and described.

DESCRIPTION

FIG. 1 is a perspective view of a head lamp showing our new design;

FIG. 2 is a side elevational view of the head lamp of FIG. 1;

FIG. 3 is a side elevational view, opposite the side view in FIG. 2, of the head lamp of FIG. 1;

FIG. 4 is a top plan view of the head lamp of FIGS. 1 to 3;

FIG. 5 is a front elevational view of the head lamp of FIGS. 1 to 4;

FIG. 6 is a bottom plan view of the head lamp of FIGS. 1 to 5; and,

FIG. 7 is a rear elevational view of the head lamp of FIGS. 1-6.

The head is shown in broken lines in FIG. 1 for illustrative purposes only.

FIG. 6

FIG. 7
